Primary Examiner — Susan E Krakower

(57) **CLAIM**

The ornamental design for a medicine ball exercise apparatus, as shown and described.

DESCRIPTION

FIG. 1 is a perspective view of a medicine ball exercise apparatus showing my new design;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof;
FIG. 7 is a bottom view thereof; and,
FIG. 8 is an alternate perspective view from that shown in FIG. 1.
